HARRY H. RALPH, OF PHILADELPHIA, PENNSYLVANIA.

PURIFIER FOR STEAM-BOILERS.

1,256,039.

Specification of Letters Patent. Patented Feb. 12, 1918.

Application filed July 10, 1916. Serial No. 108,527.

To all whom it may concern:

Be it known that I, HARRY H. RALPH, a citizen of the United States, residing at the city of Philadelphia, in the county of Philadelphia and State of Pennsylvania, have invented certain new and useful Improvements in Purifiers for Steam-Boilers, of which the following is a specification, the present invention being an improvement 10 upon the apparatus described and claimed in United States Letters Patent granted to me under date of December 8, 1914, and numbered 1,120,405, and United States Letters Patent granted to me under date of 15 November 16, 1915, and numbered 1,160,651.

The purifiers for steam boilers set forth in the above mentioned patents, while proving generally satisfactory in use, have demonstrated the practicability of making certain changes to render the same more efficient and commercially valuable.

The principal object of the present invention is to overcome certain disadvantageous features present in the apparatus disclosed in my aforesaid patents and provide improved apparatus wherein certain new and novel arrangements and combinations of parts are embodied for effecting a more efficient, practical and commercially valuable purifier for steam boilers. A further object of the present invention is to provide apparatus of this character wherein boiler incrusting solids are precipitated by the application of sufficiently high temperature and whereby any floating solids are arrested to prevent egress to the boiler interior.

Other and further objects of the present invention reside in the providing of such details of construction as will hereinafter appear.

The invention consists of the improvements hereinafter described and finally claimed.

The nature, characteristic features and scope of the invention will be more fully understood from the following description taken in connection with the accompanying drawings forming part hereof and in which:

Figure 1 is a view partly in elevation and partly in section of the purifier embodying the invention;

Fig. 2 is a top or plan view thereof;

Fig. 3 is a view in cross-section of a steam boiler equipped with the purifier of the invention; and

Figs. 4 and 5 are fragmentary views illus-

trating details of construction hereinafter referred to.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, 1 designates an ordinary horizontal tubular boiler contained within which is the feed-water purifier 2 of the invention. As shown, the purifier consists of a number of flanged sections *a*, *b*, *c*, *d* and *e* bolted together as at 3, to form a casing. The number of sections is immaterial. Leading to the purifier 2 from a pump, not shown, is a feed-water inlet connection 4. The inlet connection 4, see Fig. 2, is spaced apart from and extends entirely around the purifier 2 at the top thereof and connects with the inlet section *a* of the purifier as shown. This connection 4 is provided with a funnel-like member 5 which member is equipped with a check valve 6 of the inwardly opening type and of any desired make. The opposite end of the purifier 2, that is section *e*, has leading therefrom a pipe 7 which may be connected with the valved blow-off (not shown) of the boiler 1. Adjacent the upper part of section *a*, of the purifier and upon each side thereof are openings or ports 8 and 9. Leading from these ports are horizontally disposed pipes 10 each of which terminates in a vertical section 11 which extends below the water level in the boiler 1. Each pipe 10 is provided with an inwardly opening check valve 10', of any desired form, which valves as shown in Fig. 3 are located at points beyond the connections of pipes 12. Between the check valves 10' and the ports 8-9 each pipe 10 has connected therewith a depending pipe 12. The pipes 12 in turn terminate in horizontal sections 13 which parallel the purifier casing in a plane therebelow each section 13 being provided with a check valve 14 which opens outwardly. Connecting with each of these horizontal sections 13 are a series of pipe connections 15 arranged to extend downwardly through the boiler 1 to

within a short distance of the bottom thereof. These pipe connections 15 preferably pass between the boiler tubes 16 as clearly shown in Fig. 3. Within section *a* of the 5 purifier, adjacent the feed water inlet opening 17 and immediately forward of ports 8—9 is a vertically disposed baffle plate 18 which extends from the top of said section to within a short distance of the bottom 10 thereof and preferably formed integral with said section. Extended at right angles from the back of said baffle plate, substantially midway of the height of said section *a*, is a horizontally disposed baffle plate 19 preferably formed integral with said baffle plate 15 and said section. Secured within adjacent sections *b* and *c* and preferably formed integral therewith are horizontally disposed baffle plates 20 arranged in the same plane 20 as the baffle plate 19 and which in effect are continuations of the latter. The combined baffle plates form a somewhat T-shaped construction. Obviously, the number of purifier sections having therein baffle plates is 25 immaterial. The advantages of such arrangement of baffles will be explained in connection with the operation of the purifier to be presently described. Bolted between sections *c*—*d* of the purifier is a plate 30 21. This plate has openings 22 and 23 near the top and bottom thereof respectively, to allow of the free passage of water therethrough but is provided with a central web 24 which abuts against and forms a tight 35 joint with the horizontal baffle plate 20 of section *c*. A horizontal grating 25 is placed within the last sections *d*—*e* of the purifier at a level lower than the horizontal baffle plates of the other sections. This grating 40 comprises a plate having openings therethrough and is provided with beveled sides and is of a length equal to sections *d*—*e*. In practice, the grating is fitted within said sections so that the beveled sides are supported upon the inclined walls of sections 45 *d*—*e*. End plate 26 maintains the grating in abutting position with the web of plate 21. Of course, it will be understood that the grating may be of such size as to fit 50 within one or more sections of a purifier according to conditions under which a purifier is working. Removably seated upon the grating 25 is a perforate basket or cage 28 preferably constructed of wire mesh. Such 55 basket or cage in cross-section is shaped to fit snugly within the rear sections *d*—*e* as clearly illustrated in Fig. 3 and is of a length equal to the grating 25. Thus the cage is securely clamped between the plates 60 21 and 26. In practice, this cage is filled with a suitable filtering material as quartz sand. Experience has dictated that good results are obtainable by constructing the cage in a manner as shown in Figs. 4 and 5. The 65 former figure illustrates the inner and the

latter figure the outer end of the cage. A flanged plate 29 is employed for closing the inner end of the cage and to the inner portion of flange of which plate is riveted or otherwise secured wire mesh 30. At the 70 outer end of the cage the wire mesh is secured to the inner circumference of a ring-like member 31. The cage thus constructed is filled with the filtering material and a flanged plate 32 provided with a handle 33 75 is fitted within said member 31 and bolted, riveted or otherwise secured in position as shown in Fig. 5. A filtering cage thus constructed may be readily inserted through the rear sections of the purifier. Straps 34, 80 see Fig. 3, are secured to the boiler top for supporting the feed connection 4. At the same time the straps support the purifier as a whole. This construction forms means for suspending the purifier within the boiler in 85 a rapid, cheap and efficient manner.

In practice it is endeavored to keep the water line within the boiler 1, even with the funnel-like member 5 so that the water outlet openings or ports 8—9 are consequently below the water line, and it may be here remarked that normally pressure within the purifier is slightly in excess of pressure within the boiler. In feeding raw water which usually contains silica, oxid or 90 iron and alumina, lime and magnesia to the purifier 2, it first impinges against the baffle plate 18 and the sediment in the water caused by the partial precipitation of the above solids as they pass through the heated 95 inlet pipe 4 is directed to the bottom of the purifier which sediment tends to settle within the chamber 35 that extends along the base thereof. In this connection the baffles 20 serve to further direct sediment toward 100 the chamber 35 during the agitation of water which occurs at the inlet end of the purifier. In introducing water within the purifier, the baffles 20 tend to cause it to flow toward the extreme outer end of the 105 purifier. The water then, in order to find its way out of the purifier through ports 8—9 is forced to pass through opening 23 in plate 21 and rise through the filter and thence back through opening 22 along the 110 upper chamber 36 of the purifier to the ports 8—9 whence it escapes to the boiler. In rising through the filter any solids that have not been deposited in the lower chamber 35 and particularly those solids which 115 float will be arrested by the filter. The water will find its way to the boiler through pipes 10, 12, 13 and 15. These pipes also serve to permit the escape of air which may enter the purifier with the feed water. 125

The above described arrangement of parts permits of a gentle flow of feed water within the purifier and also serves to permit of a maximum amount of precipitation of solids, due to the great heating surface of pipe 130

4 before delivery of water to the boiler. It is to be noted that the pipes 15 may be extended, if desired, to what is termed "dead points" particularly in marine and locomotive boilers, in order to increase circulation therein. Further the filter arrests any floating solids so that the water passing to the boiler is to all intents and purposes free of solids of all kinds. Thus scum and the like 10 in the boiler is eliminated so that certain of the skimmers or funnel-like members shown in my former patents may be dispensed with.

It is thought that the operation of "blowing off" the boiler will be understood by reference to my aforesaid patents without detailed description thereof herein, but it should be noted that when the "blow-off" valve is opened, water enters the purifier 15 through pipes 11 past the inwardly opening check valves 10' and passes through the filter above the baffles 20 and downward through the filter, thus causing the filter to be cleansed of any solids which are then 20 blown out through the blow-off pipe 7 by the water which enters the pipe 4 through the funnel-like member 5 past inwardly opening check valve 6 and which water washes out any solids that may have been 25 deposited in the pipe 4 and in the bottom chamber 35. It should also be noted that during the "blow-off" operation the check valves 14 are closed so that the water in the 30 boiler cannot be sucked back into the purifier.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be 40 understood that the same is susceptible of modification in various particulars without departing from the spirit or scope of the invention or sacrificing any of its advantages.

50 What I claim is:

1. Apparatus of the character stated embracing a casing the inlet end of which is provided with a vertically disposed baffle plate and the blow-off end of which is provided with 55 a filter cage having a closed inner end, a horizontally disposed baffle plate interposed between said vertical baffle plate and the closed end of said cage, inlet and blow-off connections for the casing, means for feeding purifier water to the boiler, and independent means for the admission of boiler water to the purifier upon opposite sides of said baffle plates and cage.

2. Apparatus of the character stated embracing a casing the inlet end of which is

provided with a vertically disposed baffle plate and the blow-off end of which is provided with a filter cage having a closed inner end, a horizontally disposed baffle plate interposed between said vertical baffle plate 70 and the closed end of said cage, a feed water connection extended around the casing provided with a boiler water intake which connection establishes communication with the casing upon one side of said baffle plate and cage, means for feeding purifier water to the boiler from the opposite side of said baffle plates and cage and similarly located means for the admission of boiler water to the purifier.

3. Apparatus of the character stated embracing a casing the inlet end of which is provided with a vertically disposed baffle plate and the blow-off end of which is provided with a filter cage having a closed inner end, a horizontally disposed baffle plate interposed between said vertical baffle plate 75 and the closed end of said cage, a feed water connection establishing communication with the casing upon one side of the baffle plates 80 and cage, a boiler water intake for said connection operative during a "blow-off" period, a blow-off connection, means for feeding purifier water to the boiler from the opposite side of said baffle plates and cage, mediums therefor for preventing ingress of 85 boiler water, independent means for admission of boiler water to the purifier above the horizontal baffle plate and cage and during a "blow-off" period and mediums therefor for preventing escape of purifier water during 90 normal working conditions.

4. Apparatus of the character stated, embracing a casing the inlet end of which is provided with a vertically disposed baffle 105 plate and the blow-off end of which is provided with a filter cage, having a closed inner end, a horizontally disposed baffle plate interposed between the vertical baffle plate and said closed end of the cage, a feed 110 water connection establishing communication with said casing upon one side of baffle plates and cage, a blow-off connection, means at the inlet end of the casing and upon the opposite side of said baffle plates 115 and cage for feeding purifier water to a boiler, and means similarly located for the admission of boiler water to the purifier.

5. Apparatus of the character stated embracing a casing made up of a series of sections, a plate having top and bottom water passages, therethrough secured between adjacent sections, a grating fitted within at least one section beyond said plate, a filter cage seated upon said grating having its inner end in abutting relation with the unapertured portion of said plate, a baffle plate extended forwardly of the casing from said unapertured portion of the plate and inlet and blow-off connections for the casing.

6. Apparatus of the character stated embracing a casing having inlet and blow-off connections, a substantially vertically disposed baffle plate at the inlet end of the casing, a substantially vertically disposed partition apertured top and bottom located adjacent the blow-off end of the casing, a substantially horizontally disposed baffle plate connecting the said baffle plate and partition, and filter means spaced top and bottom from the casing interposed between said partition and the blow-off end of the casing, whereby the casing is provided substantially from end to end with superimposed chambers.

Copies of this patent may be obtained for five cents each, by addressing the "Commissioner of Patents, Washington, D. C."

7. Apparatus as described in claim 6, characterized by means connecting the uppermost chamber for the egress of purifier water.

8. Apparatus as described in claims 6 and 20, characterized by independent means connecting with the uppermost chamber for the admission thereto of boiler water.

In testimony whereof, I have hereunto signed my name.

HARRY H. RALPH.
